UNITED STATES PATENT OFFICE.

WALTER WILKINSON, OF PROVIDENCE, RHODE ISLAND, ASSIGNOR TO THE GORHAM MANUFACTURING COMPANY, OF SAME PLACE.

DESIGN FOR ORNAMENTATION FOR THE HANDLES OF SPOONS, &c.

SPECIFICATION forming part of Design No. 17,277, dated April 19, 1887.

Application filed March 14, 1887. Serial No. 230,910. Term of patent 7 years.

To all whom it may concern:

Be it known that I, WALTER WILKINSON, a citizen of the United States, residing at Providence, in the county of Providence and State of Rhode Island, have invented a new and original Design for the Ornamentation of the Handles of Spoons, Forks, Knives, &c.; and I do hereby declare the following specification, taken in connection with the accompanying illustrations, forming a part of the same, to be a description thereof.

This design relates to the ornamentation of the handles of spoons, forks, knives, ladles, &c.; and it consists in certain features herein-after described and claimed.

In the accompanying illustrations, Figure 1 represents the front or face of the handle of a spoon, and Fig. 2 the rear or back of the handle of a fork, ornamented with the design.

As shown in Fig. 1, the front or face of the handle is ornamented by a shield, *a*, which is surmounted by a crown, *b*. Above the shield and crown are arranged the leaf-and-bead scrolls *c* and the fan-shape or "palm" ornament *d*. Below the shield is arranged the leaf-and-bead ornament *f*, which extends down the handle to the point *g*. The rear face or back of the handle has a leaf-and-scroll ornament, *h*, which extends downwardly across the same from one edge. Above this ornament is an open field, *k*, upon one side of which a leafy spray, *l*, is arranged, extending inwardly from the edge.

What I claim, and desire to secure by Letters Patent, is—

35

1. In a design for the ornamentation of the handles of spoons, forks, knives, &c., the shield *a*, surmounted by a crown, *b*, leaf-and-bead scrolls *c*, and fan-shape ornament *d*, and the leaf-and-bead ornament *f*, extending below 40 said shield, substantially as described and shown.

2. In a design for the ornamentation of the handles of spoons, forks, knives, &c., the leaf-and-scroll ornament *h*, surmounted by an open 45 field, *k*, upon one side of which is arranged the leafy spray *l*, substantially as described and shown.

3. In a design for the ornamentation of the handles of spoons, forks, knives, &c., the 50 shield *a*, crown *b*, leaf-and-bead scrolls *c*, fan-shape ornament *d*, and leaf-and-bead ornament *f*, arranged upon one face of the handle, and the leaf-and-scroll ornament *h* and leafy spray *l*, arranged upon the opposite face of the 55 handle, substantially as described and shown.

In testimony whereof I have hereunto signed my name this 28th day of February, A. D. 1887.

WALTER WILKINSON.

Witnesses:

EDSON SALISBURY JONES,
HENRY J. STAPELTON.
